UNITED STATES PATENT OFFICE.

WILLIAM W. BUCHER, OF CHICAGO, ILLINOIS, ASSIGNOR, BY MESNE ASSIGNMENTS,
TO KOHLER COMPANY, OF KOHLER, WISCONSIN, A CORPORATION OF WISCONSIN.

AUTOMATIC ELECTRIC GENERATING UNIT.

1,422,027.

Specification of Letters Patent. Patented July 4, 1922.

Application filed March 20, 1919. Serial No. 283,910.

To all whom it may concern:

Be it known that WILLIAM W. BUCHER, citizen of the United States, residing at Chicago, in the county of Cook and State of Illinois, has invented certain new and useful Improvements in Automatic Electric Generating Units, of which the following is a specification.

My invention relates to improvements in self contained automatic electric generating units and it consists more especially of the features hereinafter pointed out in the annexed claims.

Some of the purposes of my invention are: (1) to provide an entirely automatic electric generating unit which supplies current at a normal commercial voltage adaptable to standard accessories without the necessity of using many cells of storage battery; (2) that is self starting without the use of a separate starter; (3) that eliminates the use of large capacity storage cells; (4) that employs a low voltage current momentarily on high voltage service mains to automatically start the system by utilizing the shunt coil and armature only of a compound wound generator of standard voltage rating to cause such generator to act as a motor and thus start the system; (5) that automatically controls the speed of the engine according to the fluctuations of load by the manipulation of the engine throttle and choker simultaneously; and (6) that automatically through the intermediary of a governor actuated by the engine, or by any other means, prevents the generator remaining at low voltage after having been subjected to a low voltage current while being used as a motor to start the engine.

With these and other ends in view I illustrate in the accompanying drawings such instances of adaptation as will disclose the broad underlying principles without limiting myself to the specific details shown.

Fig. 1 is a side elevation, from a photograph, of a complete self-contained generating unit as employed in actual practice.

Fig. 2 is a diagrammatic view of the stopping relation of the interconnected circuits, all inactive circuits being shown in dotted lines.

Fig. 3 is a similar view showing a portion of Fig. 2 in a modified relation, instancing

a variation of the duplex magnet circuit connections.

Fig. 4 is a diagrammatic view of the circuit relation existing during the first and second stages of a starting operation. In this figure the circuits which are not in use are also shown in dotted lines.

Fig. 5 is also a diagrammatic view similar to Fig. 2, showing the third stage of starting, the dead circuits being also designated by dotted lines, as in the other figures.

Fig. 6 is a diagrammatic view of the full running relation of the several parts of a complete system, inactive lines being shown by means of dotted lines.

As several features of this invention are made the subject of separate applications, notably, (1) the control switch 8; (2) the duplex magnet 28; and (3) the governor 20 in relation to the throttle and choker control, these will not be described in great detail, except in so far as cooperating features are necessary to a clear understanding of the purpose and the basically essential parts of my present system. In other applications I have disclosed earlier stages of development which however do not specially relate to the present disclosure, except as to the broad general ground hereafter referred to. Several improvements which have been made under the exacting demands of actual practice have still further matured the basic ground of these inventions.

This ground, among other features, broadly covers a generator of normal high voltage rating, an internal combustion engine for operating the generator, an ignition system for the engine, a low voltage battery, high voltage service mains, and automatic switching means responsive to the minimum practical demand for current on such mains or to a discontinuance of such demand.

It also comprises a system which is adapted to temporarily use the low voltage battery current on the high voltage service mains, their accessories, the switch and the high voltage generator to start the system automatically, and further to stop the engine and the system when the demand for current on the service mains ceases.

A further broad purpose, more concisely stated comprises the following features:— to temporarily use a normal high voltage

generator—connected to an internal combustion engine—for starting purposes on current from a low voltage battery, to immediately thereafter have the generator deliver 5 high voltage current as needed to supply standard voltage accessories.

Prior efforts in this field have essayed the use of a double ended armature in the generator, one end for a low voltage starting 10 current and the other end for a high voltage service current. Such a proposal is embodied in my Patent No. 1,332,707, dated March 2, 1920. Under that plan the generator must be of a special type, making its cost nearly 15 double that of one whose armature is standard throughout.

Whether one or the other type of generator is used is immaterial, as the broad principle of temporarily using a low voltage 20 current on normal high voltage service mains to set the plant in operation applies to either of the types, or to those in which a separate low voltage starter is used. This ground has been disclosed in practical tests antecedent to this application.

A differentiating factor which clearly sets this invention apart from other efforts disclosed in the prior art, in which compressed air cooperating means have been used, or 30 a battery of the same voltage as the service voltage of the generator has been employed, is found in the existing current limitation of a single high voltage lamp when subjected to a fractional part of its normal 35 voltage rating, and the inclusion of a control responsive to such limited current by which an electric generating system is set into operation to subsequently supply current to the high voltage accessories at their 40 normal rating, regardless of the specific type of generator that may be used.

Such a system forms the nucleus around which my several related inventions have been developed, and whatever degree of 45 specialization has been attained the fundamental features play an important rôle in each of the developing stages.

The terms, high, normal, or standard voltage, for the purpose of this description, 50 designate approximately 110 and 115 volts; and the term, low voltage, for a similar purpose, may mean 24 volts, or 6 volts, or any practical voltage necessitating the use of a minimum number of cells to complete 55 each starting operation.

For the purpose of this exemplification, the system comprises a self contained unit, without a switch board or other extraneous 60 cooperating devices. In installing the same, all that is necessary is to connect the terminals of the generator to existing service mains, connect the cooling system if separately supplied, turn on one of the usual 65 lamps found on such mains and, in an entirely automatic manner the system will at

once supply current to one or more lamps, etc., up to its full capacity as long as desired and the fuel is fed to the engine, regardless how frequently or infrequently the plant is started and stopped.

The engine 1 supports the generator 2, the governor 20, the vacuum fuel feeding system 22, the battery charging resistance 25, and it may also support the battery 26 on a suitable projecting shelf. If the battery 26 is not so supported it may be placed 70 on the floor anywhere conveniently adjacent the dynamo 2. In any event its socket terminals, not shown, are simply attached to suitable plug terminals on the switch 8 without regard to their polarity, as in practice it has been found immaterial in what relation the battery is connected.

Generator 2 is provided with the usual end-ring bearing bracket 3. At its other 85 end, next the engine, a supporting spider 4 is placed. This is attached to the generator 2 and a casting 5 which encloses the fly wheel 6. This casting is secured to the base of the engine as shown in Fig. 1. The 90 engine shaft 7, is also the armature shaft, yet in practice it is usual to have two separate shafts joined by an insulating coupling. Above the generator 2 a switch unit 8 is placed.

This switch 8 includes all the operating controls of the electrical part of the system and dispenses with the usual separate switch board. It carries a starting magnet 47 and a running magnet 48, only shown diagrammatically in Fig. 2, etc., and it also supports a duplex magnet 28—63. This duplex magnet comprises a fine wire battery starting control coil 63 and a coarse wire dynamo running control coil 28. The battery 26, 100 resistance 25, magneto 21, and the governor control 27 are the only external connections from the switch, but as these are all made in advance in completed plants the purchaser does not need to give any attention 110 to them whatever.

The engine is supplied with a carburetor 9 and a throttle 10 controls the fuel in the inlet passage 24. A choker 11 controls the admission of air to the carburetor. The 115 throttle 10 and the choker 11 are respectively controlled by the governor by links 12 and 13 connected to arm 14. This arm is pivoted at 15 and a short extension 17 cooperates with a dash pot 16 to prevent 120 "hunting." Another extension 18 carries a weight 19 to counter balance the lever system. Such a speed control for widely varying loads might be inefficiently substituted by a voltage coil controlled by the 125 dynamo, but it is believed to be much less dependable than a governor in the hands of users who are not electricians. Such a substitute would be subject to variable movement which in the very nature of things is 130

more difficult to control than a connected mechanical speed element. In all of the magnets used in this system variable movement is not used, but instead positive extremes of movement are employed.

The engine spark plugs 23 are served by the magneto 21 over line 79, in any well known manner, and the cylinder walls are cooled in the usual way by a circulating water system, not shown. The generator 2 is of the compound type, having a series coil 53 and a shunt coil 55. If further compensation is required for any reason it may be overcompounded by winding 54. Terminals 52 and 56 of the generator serve as outside connections to the switch 8 and battery 26. A separate connection 67 leads from the series coil 53 to the switch.

Without going into further details the operation of the system will be readily followed from the subsequent description. In Fig. 2, the stopping relation is shown, in which all the inactive circuits are designated by dotted lines and the one "active" circuit—the magneto ground connection 71 as a full line. Fig. 3 shows a definite short circuiting, or cutting out of coil 63 as soon as the high voltage of the dynamo comes on, to use the series coil 28 as a protection to 63. In Fig. 2 these coils are shown in parallel connection. Either expedient, or any alternative, will protect the coil 63 from injury.

The first step in starting is to turn on one or more lamps 50, etc., by means of any suitable switches 49. This connects the two service mains 59 and 60 through a very high resistance, if a single lamp is turned on, to the low voltage battery 26. In consequence of the total resistance of the circuit being high a very small amperage current will flow over it. This means that the coil 63 must be quite sensitive and its moving parts very responsive in order to control the other parts of the system without failures.

This first step causes current to flow through coil 63 to energize it and shift the bar 38, either through a solenoid acting on a movable core within fixed limits, or otherwise. In any event the movement is a positive one being limited in both directions without any intermediary positions whatever. The raising of bar 38 from off lower contacts 36 and 37 frees the primary 77 of magneto 21 of its short circuit over line 71 grounded at 81 and 82. This leaves the secondary 78 free to supply current to the spark plugs 23 over line 79 which is grounded at 80.

The circuit of this initial starting control current may be traced by following the full lines shown in Fig. 4, from the battery 26, past junction 29, line 61, past junction 30 to lower contact 31 of the running magnet 43, over the bar 39, onto "pigtail" 32, line 62 to coil 63, thence past junction 48, onto

service main 59, switch 49, lamp 50, service main 60 to junction 51, line 64 to junction 52 and thence by line 65 back to the battery.

The next starting step is to energize the starting magnet 47. This is done by magnet 70 63 moving the bar 38 to its extreme upward position where it connects contacts 34 and 35. This places the starting magnet 47 in circuit with the battery 26 over the following line, Fig. 4. In tracing this line it is 75 well to again start from the battery 26, passing junction 29, over line 61, past junction 30 to contact 31, bar 39 to contact 33, line 76, to governor control 27 and back over line 75 to upper contact 34, bar 38, contact 35; 80 to starting magnet 47 over line 70; line 74, past junction 57 to line 72, past junctions 51 and 52 on line 64; thence back to the battery over line 65.

The third stage, shown in Fig. 5 follows 85 the first two so rapidly that, to all appearances the results occur at the same moment. This stage is controlled by the starting magnet 47 which brings its bar 44 against contacts 45 and 46 to close a circuit from the 90 battery 26 to the generator 2, to set the engine in operation. The heavy current on this circuit leaves the positive side of the battery 26, passing junction 29 on line 61, branching off at junction 30 to reach contact 95 46, thence over bar 44, contact 45, line 68 to dynamo terminal 56, from where only the armature and shunt field 55 are traversed, joining at 52 to return to the battery over 65.

The system is now in operation. The heavy battery current has used the dynamo as a motor to start the engine which is supplied with ignition current from the magneto 21, shown in Fig. 5. It should be repeated that the series field 53 has not been used so far in the starting operation, but dependence has been placed entirely on the armature and the shunt field 55 of the dynamo.

As soon as the dynamo 2 operates at its rated voltage, after the governor 20 has opened circuit 75 and 76 at 27, Fig. 6, running magnet 43 comes into action through current supplied by the dynamo, independently of any contact bars, etc., whatever. It is connected at 57 to line 72, junction 51, line 64, and terminal 52 of the generator 2. The other side of the circuit leads from the magnet to junction 58 of line 67, thence over 120 the series field 53 of the dynamo to the other dynamo terminal 56.

The energizing of running magnet 43 shifts bar 39 from off the lower contacts 31 and 33 to the upper contacts 40, 41 and 42 125 and the running circuit shown in Fig. 6 is established. In tracing this circuit a start is made at the dynamo terminal 56, thence proceeding through series coil 53, line 67 to junction 58, contact 40, bar 39, contact 41, 130

line 69 to the running control magnet 28, where the presence of its current effect causes the magnet to continue to hold bar 38 raised, regardless of load fluctuations, so as 5 to keep the system in operation by not permitting the magneto to become grounded. From the magnet 28 it leads through service line 59, closed switches 49, lamps 50, or other accessories, to the returning service main 60, 10 past junction 51 to line 64 and the other terminal 52 of the generator armature and shunt field 55.

At the same time that the generator 2 is supplying service mains 59 and 60 with high 15 voltage current it is also automatically recharging the battery 26 over the following circuit which is simply identified by successive numerals, without naming the lines or junctions. From terminal 56, touching 53, 20 67, 40, 39, 42, 73, resistance 25, 66, 29, battery 26, 65, and 52 back to the generator.

As shown in Fig. 6, current from the dynamo at high voltage divides on bar 39, an extremely small part going over "pig-tail" 32, line 62 to magnet 63, rejoining the heavy current that branched off at contact 41 onto line 69 and magnet 28, at 48 leading to the service main 59. Because of this connection and the relative resistances of 30 the coils 28 and 63 being of the order .075 to .445 respectively, practically all current is cut off from coil 63, thus protecting it against the injurious effects of overheating without using any contacts that are subject to arcing as would be the case if a direct cut out was employed. These two magnets, 28 and 63 are jointly called a duplex magnet 28-63.

As instance in Fig. 3, the dynamo current coming to 40, over 67' follows 39, 41, 45 69 past junction 83, and coil 28 to the service main 59. This also practically cuts out coil 63 without the use of arcing contacts. This figure shows the junction 83 in advance of the coil 28-63 instead of at 48, beyond the coils as shown in Fig. 6. The initial energizing circuit for coil 63, free from all the other circuits is shown in Fig. 3 by dotted arrows. The "pig-tail" 32 remains in permanent connection with the bar 39 regardless of the position of the bar.

What I claim is—

1. In combination with a gas engine operated generator, a storage battery and service mains, a control switch having a fine winding in circuit with the battery and the mains in order to be energized by a service demand, an engine ignition means in a circuit controlled by the control switch, a starting switch having a winding in a circuit also controlled by the control switch, a governor operated switch included in the last mentioned circuit, a motor circuit including the battery and the generator as a motor and controlled by the motor starting switch, and a main switch having a winding connected in circuit with the generator and energized when the generator is driven by the engine, said control switch having a coarse wire winding in circuit with the mains and the generator and controlled by the main switch, said main switch having an interlock included in the starting switch winding circuit, and a charging resistance in circuit with the battery and the generator and controlled by the main switch.

a main switch having a winding connected in circuit with the generator and energized when the generator is driven by the engine, said control switch having a coarse wire winding in circuit with the mains and the generator and controlled by the main switch, said main switch having an interlock included in the starting switch winding circuit, and a charging resistance in circuit with the battery and the generator and controlled by the main switch.

2. In combination with a gas engine operated generator, a storage battery and service mains, a control switch having a fine winding in circuit with the battery and the mains in order to be energized by a service demand, an engine ignition means in a circuit controlled by the control switch, a starting switch having a winding in a circuit also controlled by the control switch, a governor operated switch included in the last mentioned circuit, a motor circuit including the battery and the generator as a motor and controlled by the motor starting switch, a main switch having a winding connected in circuit with the generator and energized when the generator is driven by the engine, said control switch having a coarse wire winding in circuit with the mains and the generator and controlled by the main switch, said main switch having an interlock included in the starting switch winding circuit, and a charging circuit controlled by the main switch and including the battery and the generator.

3. In combination with a gas engine operated generator, a storage battery and service mains, a control switch having a fine winding in circuit with the battery and the mains in order to be energized by a service demand, an engine ignition means in a circuit controlled by the control switch, a starting switch having a winding in a circuit also controlled by the control switch, a governor operated switch included in the last mentioned circuit, a motor circuit including the battery and the generator as a motor and controlled by the motor starting switch, and a main switch having a winding connected in circuit with the generator and energized when the generator is driven by the engine, said control switch having a coarse wire winding in circuit with the mains and the generator and controlled by the main switch, said main switch having an interlock included in the starting switch winding circuit.

4. In combination with a gas engine operated generator, a storage battery and service mains, a control switch having a fine winding in circuit with the battery and the mains in order to be energized by a service demand, an engine ignition means in a circuit controlled by the control switch, a starting switch having a winding in a circuit also

controlled by the control switch, a governor operated switch included in the last mentioned circuit, a motor circuit including the battery and the generator as a motor 5 and controlled by the motor starting switch, and a main switch having a winding connected in circuit with the generator and energized when the generator is driven by the engine, said control switch having a coarse 10 wire winding in circuit with the mains and the generator and controlled by the main switch.

5. In combination with a gas engine operated generator, a storage battery and service 15 mains, a control switch having a fine winding in circuit with the battery and the mains in order to be energized by a service demand, an engine ignition means in a circuit controlled by the control switch, a starting 20 switch having a winding in a circuit also controlled by the control switch, a motor circuit including the battery and the generator as a motor and controlled by the motor starting switch, and a main switch having 25 a winding connected in circuit with the generator and energized when the generator is driven by the engine, said control switch having a coarse wire winding in circuit with the mains and the generator and controlled 30 by the main switch said main switch having an interlock included in the starting switch winding circuit.

6. In combination with a gas engine operated compound wound generator and storage 35 battery and service mains a control switch having a fine winding in circuit with the battery and the mains in order to be energized by a service demand, an engine ignition means in a circuit controlled by the control switch, 40 a starting switch having a winding in a circuit also controlled by the control switch, a governor operated switch included in the last mentioned circuit, a starting circuit including the battery and the armature and 45 shunt field winding of the generator for operating the generator as a motor and controlled by the motor starting switch, a main switch having a winding connected in circuit with the armature and series field winding 50 of the generator and energized when the generator is driven by the engine, said control switch having a coarse wire winding in circuit with the mains and the armature and series field winding of the generator and controlled 55 by the main switch, said main switch also having an interlock included in the starting switch winding circuit, and a charging resistance in circuit with the battery and

the armature and series field winding of the generator and controlled by the main switch. 60

7. In automatic control switches for gas engine operated generator plants, a control switch serving both as a starting and running control, a battery supplying initial current to the control switch magnet, a starting 65 switch set into operation by the control switch, a supplemental governor control for the starting switch magnet, an engine ignition circuit made operative and inoperative by the control switch, a main switch, a 70 generator connected to the magnet thereof, service mains supplied by the generator, means controlled by the main switch to maintain the control switch in operated position 75 so long as current is delivered to the service mains by the generator and means operated by the main switch to cause the battery to be charged from the generator.

8. In combination with a gas engine operated generator and its mains, a control 80 switch serving both as a starting and running control a battery supplying initial current to the control switch magnet through the mains, a starting switch set into operation by the control switch a supplemental 85 governor control for the starting switch, an engine ignition circuit made operative and inoperative by the control switch a main switch, the generator being connected to the magnet thereof and connected to the service 90 mains through the main switch, means controlled by the main switch to maintain the control switch in operated position so long as current is delivered to the service mains by the generator, and means operated by the 95 main switch to cause the battery to be charged from the generator.

9. In combination with a gas operated generator and its mains, a control switch serving both as a starting and running control, a battery supplying initial current to the control switch magnet through the mains, a starting switch set into operation by the control switch, a supplemental governor control for the starting switch, an engine 100 ignition circuit made operative and inoperative by the control switch, a main switch, the generator being connected to the magnet thereof and connected to the service mains through the main switch, and means 105 controlled by the main switch to maintain the control switch in operated position so long as current is delivered to the service mains by the generator.

In testimony whereof I affix my signature.
WILLIAM W. BUCHER.
